COMBINATION CLOSURE AND SUPPORT HOOK
FOR A COLLAPSIBLE TUBEHarold B. Jennings, 1602 Travis Heights Blvd.,
Austin, Tex. 78704

Filed June 14, 1971, Ser. No. 153,125

Term of patent 14 years

Int. Cl. D9—07
U.S. Cl. D9—261FIG. 1 is a left side elevational view of a combination closure and support hook for a collapsible tube showing my new design;

FIG. 2 is a perspective view thereof;

FIG. 3 is a front elevational view thereof;

FIG. 4 is a rear elevational view thereof; and

FIG. 5 is a cross sectional view taken on line 5—5 of

FIG. 4.

I claim:

The ornamental design for a combination closure and support hook for a collapsible tube, as shown.
